UNITED STATES PATENT OFFICE.

OLE ROLFSEN, OF LARVIK, NORWAY.

ROCK-CUTTING TOOL.

Application filed July 12, 1922, Serial No. 574,425, and in Norway July 23, 1921.

The present invention relates to rotary rock cutting tools and has for its object to provide a mechanically operated rock cutting tool of simple and cheap construction, 5 which may serve equally well for treating plane surfaces of rock as for the purpose of boring tunnels and breaking up stones.

According to the invention the rock cutting tool comprises a head of a heavy hard 10 material such as hardened steel, said head being connected by means of a link with a rapidly rotating hub or spider.

Preferably the hammer head may be given 15 a substantially triangular shape and may be mounted with a certain amount of loose play on the free exterior end of a link, the inner end of which is again mounted with a certain amount of loose play in a hub or in the 20 free end of a spider arm fastened on a rotating hub.

Further the invention relates to the construction of the hammer head, and the connection of the latter with the loose link as 25 well as the connection of the loose link with the rotating hub or spider.

On the drawing:

Fig. 1 is a side view of the hammer and arm with one of the links removed and

Fig. 2 is a section on the line II-II of 30 Fig. 1.

The hammer 1 has a substantially triangular shape and is mounted on trunnion 2, which connects the free ends of two links 3. Trunnion 2, as will be seen on the 35 drawing, is provided with an eccentric expansion between the links 3 in order to obtain a large bearing surface between hammer 1 and trunnion 2, and at the same time keeping the exterior ends of links 3 a certain 40 distance back from the working surface of hammer head 1.

The boring 4 in the hammer head serving to take up trunnion 2 is somewhat larger than the expanded part of the trunnion 2 45 passing through the said boring and has approximately the same triangular shape as the circumference of the hammer head, the corners being heavily curved so as to fit the circumference of trunnion 2.

The inner ends of links 3 are connected 50 with an arm 5 by means of a trunnion 6, which is provided with an eccentric expansion in the same manner as trunnion 2 in order to provide a larger bearing surface 55 between arm and trunnion. Arm 5 is integral with a hub 7 mounted on a rotating

shaft 8. Said shaft may be provided with two or more similar arms 5 each carrying one cutting hammer.

When arm 5 rotates in the direction indicated by the arrow, the tool is brought to engage rock surface 9, hammer 1 will strike the rock surface with the corner, which is foremost in the direction of movement. Thereby the hammer head is rotated with 60 regard to the trunnion 2 and comes to rest with regard to the trunnion with the next corner of the triangular boring in engagement with the trunnion.

During the rotation of the hammer head 70 the striking edge of the same slips away from the rock surface and after the completion of one rotation the rock is struck with the next striking edge.

Owing to the loose play provided in the 75 connection between hammer head and links as well as between links and arm all jamming effect between hammer head and rock surface is prevented, and owing to the continual rotation the hammer head caused by 80 each stroke against the rock a uniform bore of the striking edges is obtained.

In order to minimize the friction between trunnion 6 and arm 5 it is obvious that a ball or roller bearing may be substituted 85 for the simple bearing illustrated at this point. This however need not be further described or illustrated as it is an ordinary feature of construction and does not constitute any part of the invention. 90

Claims:

1. In a rock cutting tool, a rotating shaft and hub thereon, radial arms on said hub, links pivoted with loose motion at the free end of said arms, hammer heads rotatably mounted with loose play on pivots at the free ends of said links, and the distance between the pivots being such that the hammer heads can perform complete revolutions at all times. 100

2. In a rock cutting tool, a rotating shaft and hub thereon, radial arms on said hub, twin links pivotally and loosely connected with their inner ends to the free ends of said arm, a trunnion connecting the free ends of said free links and a hammer head provided with a number of rock cutting edges loosely mounted on said trunnion between the free ends of the links, and the distance between the trunnion and the pivot being sufficient to permit the hammer head 105 to perform complete revolutions at all times. 110

3. In a rock cutting tool, a rotating shaft and hub thereon, radial arms on said hub, twin links pivotally and loosely connected with their inner ends to the free ends of said arms, a trunnion connecting the free ends of said free links, said trunnion being provided with an eccentric cylindrical enlargement between the links, a hammer head loosely mounted on said eccentric enlargement and the distance between the trunnion and the pivot being sufficient so that the hammer head is permitted to perform complete revolutions at all times.

4. In a rock cutting tool, a rotating shaft and hub thereon, radial arms on said hub, twin links pivotally and loosely connected with their inner ends to the free ends of said arms, a trunnion connecting the free ends of said free links, said trunnion being provided with an eccentric cylindrical enlargement between the links, a polygonal hammer head loosely mounted on said eccentric enlargement and the distance between the trunnion and the pivot being such that the hammer head is permitted to perform complete revolutions at all times.

5. In a rock cutting tool, a rotating shaft and hub thereon, radial arms on said hub, twin links pivotally and loosely connected with their inner ends to the free ends of said

arms, a trunnion connecting the free ends of said free links, said trunnion being provided with an eccentric cylindrical enlargement between the links, a triangular hammer head loosely mounted on said eccentric enlargement and the distance between the trunnion and the pivot being such that the hammer head is permitted to perform complete revolutions at all times.

6. In a rock cutting tool, a rotating shaft and hub thereon, radial arms on said hub, twin links pivotally and loosely connected with their inner ends to the free ends of said arms, a trunnion connecting the free ends to said free links, said trunnion being provided with an eccentric cylindrical enlargement between the links, a triangular hammer head loosely mounted on said eccentric enlargement and provided with a triangular bore having rounded corners, said rounded corners having approximately the same curvature as the cylindrical enlargement of the trunnion, and the distance between the trunnion and the pivot being such that the hammer head is capable of performing complete revolutions at all times.

In testimony that I claim the foregoing as my invention, I have signed my name.

OLE ROLFSEN.
